UNITED STATES PATENT OFFICE.

ALBERT ALEXANDER LETHERN, OF LONDON, ENGLAND, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

SLING.

1,323,701.

Specification of Letters Patent.

Patented Dec. 2, 1919.

Application filed February 17, 1917. Serial No. 149,266.

To all whom it may concern:

Be it known that I, ALBERT ALEXANDER LETHERN, a citizen of Great Britain, residing at London, England, have invented a 5 certain new and useful Improvement in Slings, of which the following is a specification, reference being had therein to the accompanying drawings.

This invention relates to slings for rifles 10 and the like and has for its object to effect certain improvements which will facilitate the manipulation of the sling when it is desired to vary its length and also enable the rifle to be carried in a more convenient manner.

As usually constructed a rifle sling comprises a strip of leather or woven fabric which is attached to the rifle by passing it 20 through the swivels thereon and the strip is provided with some form of sliding or other connection between one or each end of the sling and the main portion thereof so that the length of the sling can be varied to meet requirements. Such devices as have been 25 used for connecting the sling ends to the main part have been of the nature of slides, buckles or the like or double hooks adapted to engage the edges of the strip forming the sling. In either case, however, these arrangements lacked the simplicity and advantages which are to be found in the present improvement.

The accompanying drawings illustrate the improved rifle sling and the various ways 35 in which it can be adjusted for use.

In the drawings,—

Figure 1 is a perspective view showing a rifle with the sling attached and shortened as it would be when the rifle is to be carried 40 in the hand.

Fig. 2 shows in perspective the sling when lengthened so as to permit of the rifle being slung over the shoulder and connected to the equipment.

Fig. 3 is a similar view showing an arrangement with which the sling may be provided in order to fasten one end thereof when lengthened for slinging the rifle and when the wearer has no means of attaching the 50 sling to an equipment.

Like letters indicate like parts throughout the drawings.

The sling is formed of a strip A of woven

fabric, leather, or other suitable material, having attached to one end A' a metal piece 55 B in which is formed a key-hole slot. The metal piece is provided with a flat eye B' through which the end A' of the sling is passed and secured by sewing, riveting or otherwise. On the other end A² of the sling 60 is mounted a stud C adapted to engage the key-hole slotted piece B. To provide a firm mounting for the stud C the extreme end of the sling is conveniently inclosed in metal, for example sheet brass folded as at C' on to 65 the end of the flexible strip and secured by riveting. The stud C has a screw-threaded shank which is passed through this metal on the end of the strip and engages a nut on the other side, this nut not being shown in the 70 drawings. The stud C may however be attached in other ways. On the sling are three sliding loops D, E and F. These loops are conveniently formed of the same material as the sling itself, the latter being preferably 75 constructed of woven fabric.

When mounted on a rifle the sling A is threaded through the rifle swivels G and H the sling having been also passed through the sliding loops D, E and F. The end A' 80 of the sling is now doubled back on itself and again passed through the loop D. The end A² is also doubled back on itself and passed through the two loops E and F. If now the sling is to be shortened up to its 85 greatest extent for carrying the rifle the ends A' and A² of the sling are pulled until it is possible to connect the two ends of the sling by engaging the key-hole slotted piece B with the stud C. The loop D is now 90 pushed along the doubled strip of material up against the rifle swivel G. Similarly the loop E is pushed along until it is close up against the rifle swivel H. When in these positions the loops D and E prevent 95 the parts of the strip A from slipping or moving one with relation to the other. The third loop, F which need not necessarily be provided, is now moved until it covers the stud C, where it serves to keep the metal 100 parts securely connected together. The sling now appears as shown in Fig. 1.

If it is desired to lengthen the sling the two ends are disengaged, when it is possible to slide the two parts of one or each end of 105 the sling through its swivel and thus in-

crease the length. The sling can then be fixed and prevented from extending farther by pushing one of the sliding loops up against each swivel so that the two parts 5 of the sling are frictionally held there within the loop. Or the sling may be adjusted as follows: The member B is disconnected from the stud C and the main part of the sling is pulled up from the lower rifle swivel 10 H so as to draw the end A² carrying the stud C as far down toward the swivel as possible. As shown in Fig. 2 the two loops E and F now lie together close up against the swivel H, the sling being thus lengthened 15 as far as possible at that end and held securely by the two loops E and F. Also the stud by catching against the loop F prevents the slipping of this end of the sling. The main part A of the sling is now pulled 20 to some extent through the upper rifle swivel G so as to somewhat shorten the end A' which is left hanging free. The length of the sling A between the swivels H and G is now sufficient to enable the rifle to be 25 slung over the shoulder the sling passing across the chest of the wearer. If as is customary the sling passes over the left shoulder the end A' hangs down on the left hand side of the front of the wearer and it 30 is possible to engage the key-hole slotted piece B with a stud mounted on a suitable part of the equipment. Conveniently this stud is arranged on the upper part of a cartridge carrier mounted on or forming 35 the front portion of the belt of the equipment. Or the stud may be provided upon the adjacent brace or shoulder strap which supports the belt. In this way the weight 40 of the rifle can be largely balanced by the weight of the cartridge carrier in the front and little or no pressure is then exerted on the chest of the wearer by the main portion A of the sling which can hang loosely across 45 the chest. The length of the pendant portion A' is obviously adjustable in accordance with the position of the stud which engages the member B and to suit the convenience of the wearer. Should it be desirable 50 to shorten the sling so as to take up the slack portion across the chest this can be effected by pulling on the end of the sling which passes through the swivel G on the rifle stock. When the necessary 55 amount has been taken up the sliding loop is pressed home against the swivel so as to fix the sling.

In Fig. 3 is shown a device which may be employed if when slinging the rifle it is 60 not desirable or possible to use the member B for attaching to a part of the equipment. For instance, it may be required to sling the rifle when the man has not the full equipment on him. This device comprises 65 a slide J through which the main part A

of the sling is threaded. This slide J carries a stud J' adapted to engage the key-hole slotted member B. By suitably positioning the slide J in the length of the strip A the end A' of the latter can be firmly 70 secured by engaging the metal piece B with the stud J'. The end A' is thus prevented from hanging loose and moreover this end of the sling which mainly takes the weight 75 of the rifle, is securely held so as to prevent it from slipping through the swivel G. The loop D when pushed up against the swivel G exerts a certain amount of grip on the double part of the sling but when the metal piece B is engaged with the stud J' of the 80 slide J there is no risk of the sling gradually lengthening itself by slipping through the swivel G in consequence of the weight 85 thereon and the movements of the wearer.

As mentioned the key-hole slotted member B may be replaced by a hook of suitable shape adapted to engage an eye which is thus substituted for the stud C. In that case a corresponding eye is provided on the main equipment and if the slide J is used 90 this carries an eye in place of the stud J'.

It is desirable in most instances and particularly where the sling is used with an equipment to adjust the attachment to the lower swivel H, which in the case of a rifle 95 is that mounted on the stock, so that the end of the sling strip which carries the stud C is pulled down to its extreme limit as determined by the sliding loop or loops through 100 which it passes and as shown in Figs. 2 and 3.

As mentioned the sling may be constructed of any suitable material but preferably it is formed of woven fabric the 105 sliding loops also being constructed of the same material.

I claim as my invention:

1. A sling for a rifle or the like, comprising a strip of flexible material adapted to be passed through the upper and lower swivels of said rifle, or the like, the said strip having its opposite ends provided with interengaging connecting devices, a loop slidably embracing the lower doubled end-portion of said strip and adapted to retain said connecting devices engaged with each other, and loops slidably embracing the respective doubled end-portions of the strip and adapted to bind them adjacent the 115 swivels so as to prevent slipping through the swivels.

2. A sling for a rifle or the like, comprising a strip of flexible material adapted to be passed through the upper and lower 125 swivels of said rifle, or the like, and to have both end-portions thereof doubled-back upon the intermediate portion of the strip, the said strip having one end thereof provided with a slotted connection-piece and the 130

other end provided with a stud to enter the slot of said connection-piece, to fasten the sling in shortened condition, loops slidably embracing the respective end-portions of 5 the strip and adapted to bind them adjacent the swivels so as to prevent the strip from slipping through the swivels, and another loop slidably embracing the lower doubled end-portion of said strip, adapted to be

slipped up to retain the stud and connection-piece in interengagement.

In testimony whereof I affix my signature in the presence of two witnesses.

ALBERT ALEXANDER LETHERN.
